TRAFFIC SIGNAL

Application filed September 8, 1926. Serial No. 134,158.

This invention relates to improvements in traffic signals and more particularly to signals attached to automobiles and adapted to be operated by the driver, to display signals indicating right and left turns, stops, etc.

Among the objects of the invention are to provide a compact self contained easily attachable signal device that will present a 10 visible semaphore on the outside of the car, operated by means from within the car within easy reach of the driver. A further object is to present a maximum amount of 15 semaphore surface when exposed, that may be folded within the minimum of space when not presented in the signaling position. Other objects and advantages will appear as this description progresses.

In this specification and the annexed 20 drawings, the invention is disclosed in the form considered the best, but I do not wish to be understood as limiting the invention to this form, as it may be embodied in other forms, and it is also to be understood that in 25 and by the claim following the description, it is desired to cover the invention in whatsoever form it may be embodied.

In the accompanying one sheet of drawings, Figure 1 is a pictorial illustration of 30 an automobile having this device applied thereto. Figure 2 is a vertical section on the line II—II, of a signaling device constructed in accordance with this invention. Figure 3 is a fragmentary front elevation showing the semaphore lights and the super-posed relation of the leaves forming the semaphore.

In detail the construction illustrated in the drawings comprises the enclosing casing preferably formed in dies from sheet metal 40 in channel section, having the bottom 1 with parallel sides 2 rising therefrom and having the ends 3 and 4. About centrally of its length the enclosing casing is offset as at 5. The invention is designed to be attached to 45 the front stile of the front door of enclosed models of automobiles, adjacent to the driver. The offset 5 being provided to expose the upper or semaphore half of the casing on the exterior of the car while the control half 50 remains within the car.

The semaphore comprises a series of leaves super-posed one with the other, the lowermost leaf 6 being provided with a flange 7 along its lower edge to cover the edges of the connected leaves 8, 9 and 10, when they 55 are folded within the casing. These leaves are segmental, being wider at their outer ends and taper towards their inner ends. These narrower ends or apices are all pivoted upon a common pin 11 transversely secured across 60 the casing, spaced away from the bottom flange and adjacent to the outer edges of the walls 2 at the offset 5. These leaves 6 to 10 are inserted over the pin 11 with an anti-friction washer between to space the leaves 65 apart to prevent them chafing one against the other. Near their outer or wider ends each of these leaves is provided with an arcuate slot 12. The arc of the slot being struck on the radius from the pivotal center 11. 70 Each of these slots 12 engage a pin 13 in the contiguous leaf. The pins 13 have heads wider than the slots 12 so that all of the leaves are inter-connected and are adapted to swing on the center 11 in fan like formation, the 75 slots and pins 12 and 13 limiting the spread of the semaphore.

Both sides of the semaphores are provided with any desirable legends such as, "Right", "Left", "Stop", and the like, each of the 80 leaves from 6 to 10 containing its portion of the characters forming the legends, so that the spread semaphores will display the complete legends. These semaphores should be painted distinctive colors such as red for 85 "Stop", the word stop in white letters, the semaphore indicating a "Right" turn being a white ground with black letters, and the semaphore indicating a "Left" turn being yellow with black letters, or any other combinations of colors that may be desired or prescribed by law. The topmost leaf 10 is provided with a jointed retaining arm consisting of two parts joined by a pivot at 14 90 and having its opposite ends pivoted to the upper edge of the leaf 10 and the side wall 2 or partition 27 of the casing respectively as at 15 and 16. The length of the retaining arm is intended to spread or fan out the 95 semaphore as it drops. The respective leaves 100

8, 9 and 6 drop by gravity, assisted by momentum, to the limit of their respective slots 12 and pins 13. Any number of these semaphores may be assembled within the casing 5 to indicate the intention of the driver to stop, make a right or left turn, or "back", according to the number or semaphores assembled within the casing. These various semaphores are under remote control of individual handles within the reach of the 10 driver of the vehicle.

The preferred type of control consists of a bell crank such as 17, pivoted as 18 on a transverse pin extending across the casing 15 and fixed in the walls 2-2. The outer end of this bell crank is pivoted at 19 to the lower leaf 6 of the semaphore in front of the pivot 11, the inner end is pivoted as at 20 to the end of the connecting rod 21, that is pivoted 20 at 22 on the lever 23, which in turn is pivoted on the pin 24 extending transversely across the casing between the walls 2-2. The handle ends of the levers 23 protrude through operating slots in the bottom 4 of the casing 25 and are provided with ornamental and convenient handles 25, within reach of the driver of the vehicle.

The portion of the casing within the car is closed by the cover 26 covering the control 30 mechanism. The upper portion of the casing is divided by partitions 27 to form compartments for the various semaphores and also to provide a wall to which the retaining arm can be pivoted as at 16. When the various 35 semaphores are collapsed within the upper portion of the casing the flanges 7 practically fill the spaces between the partitions 27, for the protection of the various elements of the semaphore. Other forms of remote control 40 are available, it being understood that magnetic and electric means are the equivalent of the mechanical means shown. In the cheaper forms of the invention the lower portion of the casing and the control mechanisms may be omitted and the ends of the 45 leaves 6 extended past the pivot 11, through the bottom 1 of the casing and terminate in handles, such as 25, for direct control of the semaphores.

50 This invention operates substantially as follows: The casing is attached to the front stile of the door, in front of the driver of the vehicle, by means of screws 28 and 29 passing through the casing and being screwed 55 into the woodwork of the door stile. The offset portion 5 brings the lower portion of the casing within the confines of the vehicle and into easy reach of the hand of the operator. The sliding glass in the door is not interfered 60 with in any way, except at the top, where it can rise only to the offset portion 5, leaving about an inch or so at the top for ventilation, which is usual practice in closed cars, on the driver's side. However if it is desired that 65 the glass close the limit it is necessary to cut

a notch X out of the corner of the glass to clear the offset portion 5. When the glass is retracted within the door as is usual practice, this does in no way interfere with the general appearance or operation of the door. For 70 open cars the device may be attached to the edge of the windshield and the entire device exposed. In this case, the lower levers 25 will be reversed so that their handles project outwardly on the same side of the casing as 75 the semaphores, the driver reaching forward to handle them in the same manner as previously described for closed cars, wherein the handles extend within the inclosure.

This invention operates substantially as 80 follows: all of the semaphores being normally retracted within the upper portion of the casing. When the driver intends to make a right hand turn for instance, he reaches forward and lifts the "right" handle 25 which 85 swinging on its pivot 24 lifts the rod 21, throwing the bell crank 17 upward on its pivot 18 which pulls the stem 19 downward which pulls the leaf 6 of the "right" semaphore downward until the restraining arm 90 operates to stop the descent of the leaf 10, which causes the leaves 8 and 9 to progressively slide one upon the other until all the leaves, 6, 8, 9 and 10 are fully exposed showing the full reading of the legend "Right" on 95 the semaphore, exposed from the upper portion of the casing at horizontal. After the turn is made the driver reaches forward, pulls down upon the "right" handle 25 which 100 reverses the motion causing the bell crank 17 to push the lower leaf 6 upward, progressively picking up the leaves 8, 9 and 10 and bending the retaining arm on its pivot at 14, until the semaphore is again completely collapsed 105 within its compartment in the upper portion of the casing, ready to repeat the operation.

To retain the semaphores in the inoperative position within the casing I have provided a soft spring detent 30 fastened at one end to the upper end 3 of the casing and having a 110 notch like contour at 31, to engage the pointed ends 32 of the respective leaves forming the semaphore to frictionally retain the semaphore within the casing but with sufficient resilience to give way under the impulse of 115 the control handles 25.

All the metal parts of the device, and it is all metal with the possible exception of the ornamental handles 25 are susceptible of nickel plating or other plating to match the 120 trim of the car to which it may be applied, or for similar reasons, enameled in any desired color or contrast of colors.

For night driving the electric light globes 125 33 are provided on opposite sides of the casing adjacent to the pivot 11 of the semaphores. These lights are hooded 34, to protect the eyes of the driver and also to concentrate the light by reflection on the semaphores when they are thrown into the operative posi- 130

tion. These lights are automatically turned on and off by means of the spring contact 35 arranged in the path of the levers 17 and connected with one contact 36 of the lamp filament, the other contact of the lamp filament being on a grounded circuit 37 with the casing 1, that is in turn grounded through the chassis of the automobile, and the circuit 38 of the storage battery 39 of the automobile 10 with appropriate intermediate switches.

These lights make very good "parking lights" when the car is standing at the curb at night, by merely dropping the semaphore with the legend "Stop", it then remains illuminated and in the operative position until retracted by the operator.

Having thus described this invention what I claim and desire to secure by Letters Patent is:

20 A traffic signal comprising an elongated casing having an offset intermediate its length, a collapsible fan shape semaphore comprising a plurality of segmental slidably interconnected plates having their apices pivoted on a common pivot in said casing adjacent said offset, a detent in said casing adapted to engage said semaphore, a bell crank pivoted in said offset and to the lower leaf of said semaphore, a jointed arm attached to the top- 25 30 most of said plates and to said casing above said pivoted point, and a remote control handle pivoted in said casing and linked to said bell crank.

In testimony whereof, I have hereunto affixed my signature.

MANUEL A. CASTRO.
